C. E. CARPENTER

SANITARY HEAD COVERING

Filed May 6, 1924

FIG. 1

FIG. 2

FIG. 3

FIG. 4

FIG. 5

INVENTOR

Clarice E. Carpenter

BY

John H. Peck
ATTORNEY

UNITED STATES PATENT OFFICE.

CLARICE E. CARPENTER, OF SCRANTON, PENNSYLVANIA.

SANITARY HEAD COVERING.

Application filed May 6, 1924. Serial No. 711,312.

To all whom it may concern:

Be it known that I, CLARICE E. CARPENTER, a citizen of the United States, residing at Scranton, in the county of Lackawanna and State of Pennsylvania, have invented 5 certain new and useful Improvements in Sanitary Head Coverings, of which the following is a specification.

This invention relates to a sanitary head 10 covering adapted for use in millinery stores and to be applied to the heads of customers trying on hats to prevent soiling of the hats, and obviate chance of transmission of scalp diseases from one person to another, the invention having for an object the provision 15 of a cheap form of sanitary head covering of this type which can be discarded after use by one person.

For further comprehension of the invention, and of the objects and advantages 20 thereof, reference will be had to the following description and accompanying drawing, and to the appended claims in which the various novel features of the invention are 25 more particularly set forth.

Fig. 1 of the drawing is a plan view of my improved sanitary head cover.

Fig. 2 is a side view thereof.

Fig. 3 is a fragmentary underside plan 30 view, with parts in section, of my improved sanitary head cover.

Fig. 4 is a fragmentary side view thereof.

Fig. 5 is a detail sectional view taken on the line 5—5 of Fig. 3.

35 My improved sanitary head cover is made out of a sheet of paper which is cut to oval shape. This sheet of paper is then crimped or pleated around the outer portion thereof as at 11 the crimps or pleats extending inward in a generally radial direction and diminishing in depth toward their inner ends, these crimps or pleats stopping short of the centre of the cover at their inner ends. The crimping may be done in any ordinary 40 type of machine for this purpose. When the crimping has been finished the sheet assumes the appearance shown in Fig. 2, which conforms approximately to the shape of the top part of the human head, a sanitary cap or 45 cover being thus provided which can be placed upon the head of the person trying on hats to prevent contact of the hats with the head of the person, the cover being thrown away after use by one person.

In order to permit of fitting the cover 55 more snugly on the head of the person using it, the inner fold or reach 11^a of each pleat is formed with an inwardly tapering slit or notch, indicated generally at 14 which is of less depth and width than the depth and 60 width of the pleat, and when the cover is shaped to fit the head the two edges of this notch or slot overlap one another as shown, and it will be obvious that the size of the 65 cover will be determined by the degree of overlap of these edges.

To retain these overlapped edges in position I may strike out from the two elements 11^a the rows of tongues 15 which are adapted 70 to interlock with one another.

As will be apparent from the above description I have provided an improved form of sanitary headcover which will prevent soiling of hats, or transmission of disease, and which is of an insignificant cost. 75

Having thus described my invention what I claim as new and desire to protect by Letters Patent of the United States is as follows:

1. A sanitary head covering for the purpose specified comprising a sheet of paper having pleats extending inward from the margin thereof, the portions of the sheet constituting the inner folds of the pleats being formed with V-shaped notches entered 80 thereinto from the edge of the sheet to permit of expansion and contraction of the cover, said notches being of less width and depth than the pleats, and having their side walls overlapping one another, and means 85 adjustingly securing the said overlapping side walls together. 90

2. A sanitary head cover for the purpose specified comprising a sheet of paper having pleats extending inward from the margin 95 thereof, the inner fold of each pleat being formed with an inwardly extending notch, and having their side walls overlapping one another, and tongues on the two elements of the inner fold of each pleat adapted to interlock with one another to hold the said two 100 elements overlapped.

In testimony whereof I have affixed my signature.

CLARICE E. CARPENTER.
